UNITED STATES PATENT OFFICE

ALFRED ROSEWOOD, OF SAN FRANCISCO, CALIFORNIA

WATER FAUCET

Application filed June 30, 1928. Serial No. 289,425.

This invention relates to certain improvements in water faucets of the class which regulates both cold and hot water by the turning of the same handle on the same faucet. It also pertains to a class of faucets that are made up of two sections, one being secured to the water system when the pipes are roughed in and being adapted to receive the second section of the faucet when the building is completed or when the water is to be drawn.

It is an object of my invention to provide the building trade with a standard faucet which is durable and requires no renewing of washers, and so constructed that its first section is directly connected with the water pipes and normally kept closed by the water pressure and only becomes operative when the second section and its handle are fastened to it.

A further object is to provide a faucet which is very easily opened and closed, and may be made self-closing on the hot water side when so desired, and in which the closing parts have no positive connection with its handle and therefore are not subjected to extreme stresses caused by undue pressure brought to bear on the handle.

A further object of my invention is to provide a compound faucet on a new principle which will permit the faucet to be removed without shutting off the water pressure anywhere in the building, as metallic check valves located in the fixed section of the faucet take care of that.

A further object of my invention of a new faucet is to eliminate leaking faucets, and to reduce the number of handles and concealed fittings, and of perforations in the wall and floors, bathtubs and wash stands, etc.

The special advantages of my invention and further objects thereof will be made evident hereinafter.

Reference is to be had to the accompanying drawings forming a part of this specification. Similar numerals refer to similar parts throughout the several views.

Fig. 1 shows a front view of my faucet;

Fig. 2, a vertical section through the faucet;

Fig. 3, a front view of the fixed section of my faucet on the line 3-3 of Figure 4;

Fig. 4, a horizontal section through the faucet;

Fig. 5 is a rear view of a washer used in my faucet; and

Fig. 6, a perspective view of an operating member used in my faucet.

It is evident that this faucet will be serviceable on any popular patterns of tubs, sinks and wash stands where cold and hot water is used.

I prefer to construct this faucet in the following manner:

In Fig. 2, I show the fixed cylindrical section 4 threaded externally as shown at 5 and formed with ports 7 into which the pipes 5' may be threaded.

This section is divided longitudinally by a central wall 8, and transversely by a wall 10', having an annular bushing 10 on each side of the longitudinal wall with check valves 9 in the bushings, which are free to slide from their seats by being provided with guide strips 10'', which permit of free flow of water when the check valves are lifted from their seats by the rods 11 projecting from the movable section 11' of the faucet. The fixed section being secured in the pipe system of the building, the water pressure can be turned on without any intermediate shut-off valves so far as these outlets are concerned as the check valves 9 close immediately when pressure is applied to their base 9'.

The removable section 11' of the faucet consists of a tubular casing 11' closed at one end and formed with holes 13 that align with the bushings in the fixed sections. Screws 12 hold the sections together. The movable section at its joining end has a rounded flange 14 encircling the end of the fixed section and an interposed gasket 15 shown in detail in Fig. 5 and made of rubber or pressed-out leather.

From the inner face of the casing extend two lugs 16 which serve as guides for the heads 17 secured to the rods 11 which have the valves 26 for the holes 13 fastened thereto.

These valves are made of material that water will not distort and are partly guided by the walls of the chambers in which they move.

5 A cross-piece 25 is made slideable on the rods 11 with a certain freedom of play, and is made to bear against the valve heads 17 for seating the valves 26 by means of a spring 24, one end of which bears against the end of the movable section and which is centered by a projection 24'.

10 Transversely supported in the front end of the removable section, in the plane of the rods 11, is the operating stem 19, journaled in the bearing 18 at one end and in the wall of the casing at the other end as shown at 21. A packing gland 20 prevents leakage at the bearing. This operating stem is shown in detail in Fig. 6 and has two cams 23 and 23' thereon which are adapted to act on the valve heads 17, one cam becoming active on a right hand turn of the stem and the other on a left hand turn. The cam 23' has a reverse cam 23'' associated therewith which becomes active when the cam 23 is turned beyond a predetermined degree. A handle 30 is used for manipulating the stem 19.

15 The front end of the removable section is closed by means of a cap and an outlet is provided in the spout 28. A soap dish 21' may be made to surmount the faucet.

20 The operation of my faucet is as follows: When the handle is turned in a counterclockwise direction as viewed in Fig. 4, the cam 23 pushes its valve 26 from its seat and immediately thereafter also opens the corresponding check valve so as to cause hot water to be dispensed. After the turning movement has been continued to a predetermined degree, the cam 23'' becomes active on the second valve and allows cold water to mix with the 25 hot water. The turning movement is stopped when the straight wall of the cam 23' reaches the valve head of the cold water valve.

30 On a clockwise turning of the stem, the cam 23' is made to operate the cold water valve and the turning movement is stopped when the straight wall of the cam 23 abuts with the valve head of the hot water valve.

35 In case it is desired to make the hot water valve self-closing, a spring 27 having one end bearing on the lug 16 and its other bearing on the straight face of the cam 23' may be used for returning the stem to neutral position when the handle is released.

40 I claim as my invention:

45 1. A faucet having a receiving chamber with two compartments adapted for connection to a cold and hot water supply respectively and a check valve in each compartment 50 adapted to be held in closed position by the pressure of the water, and a discharge chamber having a base for separating said chambers, said base having holes for registering with said compartment, and means for regulating the flow through each of said holes.

55 adapted to engage with the check valves for opening the same against the pressure of the water supply.

60 2. A faucet of the character described comprising a body portion containing a multiple of receiving chambers adapted for connection to a multiple of supply sources, a common discharge chamber and a base for separating the discharge chamber from the others with openings therein for 65 allowing water to enter the discharge chamber from each of the others, a gasket held in said base having valve seats thereon, a multiple of sliding rods supported in the body each having a valve thereon, pressure means 70 for forcing said valves on their seats and a member supported in the body portion having means thereon for operating one or more of said sliding rods.

75 In testimony whereof, I have hereunto set 80 my hand at San Francisco, California, this 26th day of June, 1928.

85 ALFRED ROSEWOOD.
